UNITED STATES PATENT OFFICE

WILLIAM C. TRIPP, OF BUFFALO, NEW YORK

HORSESHOE AND FASTENING MEANS THEREFOR

Application filed January 23, 1929. Serial No. 334,458.

This invention relates to an improved horseshoe and retaining means therefor, and has more particular reference to that species wherein the horseshoe is held firmly, but detachably, upon the hoof without utilizing nails.

As is intimated in the above, I am well aware of the fact that it is not broadly new in this art to employ a horseshoe and to provide means for cooperation with the horse's hoof for adequately holding the shoe in place. It follows, therefore, that my principal aim is to generally improve upon the structures of this class by providing one which is distinguished by the presence of a different type of shoe, and a novel retaining device associated therewith.

An outstanding feature and advantage is predicated upon the utilization of a pair of practical adjustable heel clamps, and a shoe whose end portions are constructed to intimately cooperate with these clamps.

An equally important and contrastingly new construction is embodied in the hoof-engaging retaining means which is characterized principally by a flexible and adjustable shackle.

Other minor details will become more readily apparent from the following description and drawings.

In the drawings:

Fig. 1 is a side elevational view of one embodiment of the invention showing it applied;

Fig. 2 is a top plan view, with a portion shown in section and with the shoe removed from the hoof;

Fig. 3 is a fragmentary detail sectional view taken approximately upon the plane of the line 3—3 of Fig. 2;

Fig. 4 is a perspective view of the heel clamp employed in this particular embodiment of the invention;

Fig. 5 is a view like Fig. 1, showing a different embodiment of the invention;

Fig. 6, like Fig. 2, is a top plan view of this embodiment of the invention;

Fig. 7 is a sectional view taken upon the plane of the line 7—7 of Fig. 6; and

Fig. 8 is a perspective view of the heel

clamp utilized in the last-named embodiment of the invention.

Attention is first invited to Figs. 1 to 4 inclusive. In these figures the reference character 9 designates generally the complete shoe which, as is shown, is of customary configuration and provided with detachable calks 10 at the front and rear. At the center of the front is an upstanding abutment 11 shaped to correspond to a complementary portion of the hoof, and this is provided at its top with a hook 12. On opposite sides of the abutment 11 are shorter abutments 13. These three abutments constitute stops against which the fore portion of the hoof is placed.

Formed integral with the end portions at the rear of the shoe and disposed opposite each other are inwardly and radially extending lugs 14 disposed in a horizontal plane. As detailed in Fig. 3 each lug is formed in its top and bottom with recesses. By thus casting the lugs, I provide a central web 15 which is in turn provided with an elongated slot 16.

It is with these lugs that the heel clamp 17 cooperates. Each clamp is the same in construction. As shown in Fig. 4 the clamp comprises an upright portion 18 of the configuration shown terminating in a curved extremity 19 constituting a lip engaging behind the hoof. This portion 18 carries a hook 20 and a centrally disposed horizontally arranged screw-threaded eye 21. This eye is of a depth corresponding to the upper recess in the lug 14 and fits in the lug as shown in Fig. 3. Cooperating therewith is a retaining screw 22 which extends through the slot as shown and serves to adjustably attach the clamp to the shoe.

The aforesaid shackle is generally designated by reference numeral 23 and is composed of a plurality of cooperating parts organized in the manner shown to provide the desired binding force upon the hoof. For instance as detailed in Fig. 2, this shackle includes a two-part turnbuckle device which is centrally arranged to engage the crown portion of the hoof. This turnbuckle device includes a pair of screw-

threaded coupling members 24 attached to each other by a link 25 and attached to small chainlets 26 through the medium of the right-angularly shaped brackets 27 and connecting bolt 28. Thus the desired flexibility is secured. The chainlets are connected with the hooks 20 on the aforesaid clamps 17. Moreover, a supplemental chainlet 29 is provided, this being connected with the link 25 and with the first-mentioned hook 12. This multiple-part shackle conveniently conforms to the contour of the hoof and securely holds the shoe in place and obviates the necessity of using nails and other 10 fastening elements of a similar type. The functioning of this shackle is enhanced through its cooperation with the adjustable heel clamps. In other words it is thought that the adjustability of these clamps coacting with the binding force gives the structure an adequate fettering action. Consequently, a dependable retaining device is thus provided.

Considering now the embodiment of the invention shown in Figs. 5 to 8 inclusive, it will be observed that the shoe is generally indicated at 30 and that it is provided with an upstanding integral abutment 31 at the center of the crown portion which terminates in an oblique apertured ear 32 in order to accommodate an adjusting bolt 33. Then on opposite sides of this abutment are the short complementary abutments 34. Moreover there are the usual calks 35 and the special horizontal recessed lugs 36. Here again the web portions of the lugs are formed with slots 37 as detailed in Fig. 7. These lugs serve to accommodate the duplicate clamping devices 38. The clamping device comprises an upstanding portion 39 having a chain hole 40, a central horizontal screw eye 41 and a laterally directed lip or extension 42. As in the other form of the invention, I also utilize small retaining screws 43 for adjustably connecting the clamps with the lugs. It is to be noted in connection with these clamps that they are adjustable radially and also have a pivotal motion and this double action permits accurate adjustment.

The shackle is designated by the reference character 44 and comprises chainlets 45 connected with the clamps 38 through the medium of the chainlet openings 40. The opposite end links of the chainlets are engaged with hooks 46 on the right-angular brackets 47 which are fastened by bolts 48 to the curved coupling member 49 of the single turnbuckle structure. This turnbuckle is generally designated by the reference character 50. It is to be noted however that it is formed with a central vertical screw-threaded hole to accommodate the stem of the aforesaid bolt 33. In this way the central portion of the shackle can be adjusted up or down to obtain a more secure binding

action and to guard against accidental displacement in case the shackle is struck against an obstruction.

A careful analysis of the description in conjunction with the drawings will reveal improvements and contributions to the art cooperating in producing an economical and practicable device which will undoubtedly fulfill the requirements of an invention of this class. Persons skilled in the art to which the invention relates will obtain a clear understanding of the invention and its prominent distinctions. Consequently a more lengthy description is regarded as unnecessary.

Minor changes in shape, size and rearrangement of parts coming within the field of invention claimed may be resorted to in actual practice if desired.

I claim:

1. In a structure of the class described, in combination, a horseshoe provided at its front with a centrally disposed rigid upstanding vertically curved toe abutment, the rear end portion of said shoe being provided with oppositely disposed horizontal slotted lugs, a pair of heel clamps having portions pivotally and adjustably connected with said lugs, and a hoof-engaging shoe retaining device connected at its opposite ends with said clamps and having its intermediate portion connected with said abutment.

2. In a structure of the class described, in combination, a horseshoe provided at its front with a centrally disposed rigid upstanding vertically curved toe abutment, the rear end portion of said shoe being provided with oppositely disposed horizontal slotted lugs, a pair of heel clamps having portions pivotally and adjustably connected with said lugs, and a hoof-engaging shoe retaining device connected at its opposite ends with said clamps and having its intermediate portion connected with said abutment, said retaining device being in the form of a multi-part flexible shackle including a turnbuckle and chainlets connected with the turnbuckle and with said clamps.

In testimony whereof I affix my signature,

WILLIAM C. TRIPP.
